UNITED STATES PATENT OFFICE.

ALVADER D. HORNE, OF HAVERHILL, MASSACHUSETTS.

ADJUSTABLE DOUBLE-BURNER TOOL-HEATER.

1,148,089.

Specification of Letters Patent. Patented July 27, 1915.

Application filed March 27, 1915. Serial No. 17,357.

To all whom it may concern:

Be it known that I, ALVADER D. HORNE, residing at Haverhill, in the county of Essex and State of Massachusetts, have invented 5 certain new and useful Improvements in Adjustable Double-Burner Tool-Heaters, of which the following is a specification.

In the art of manufacturing shoes, edge setting machines have come into use which 10 are provided with reversible burnishing irons consisting of a shank and two diverging irons, one for setting the sole edge and the other usually for the heel setting operation. In order to keep the iron in use at 15 the proper temperature, a gas flame burner is usually provided to direct a flame on the back of the tool that is being used, the other tool being out of the range of the heating flame when not in use. This manner of heating the tool is objectionable in that when 20 it is necessary to turn the tool around to bring the other iron into operative position, much time is lost before the other iron is heated up to its proper burnishing temperature.

It is therefore the principal object of my present invention to provide a burner that will give a double-flame, one flame of which being constantly directed against the tool 30 that is to the front and in use, while the other flame may be kept directed against the rear or idle tool to maintain it at the desired temperature so that it can be instantly used when brought into operative position, 35 means being provided whereby the flames can be relatively adjusted or regulated to give the same degree of heat or different degrees of heat as may be required to maintain a definite even temperature in both tools, 40 while the edge setting operations are being performed.

The invention therefore resides in those novel features of construction, combination and arrangement, all of which will be first 45 fully described, then be specifically pointed out in the appended claims, reference being had to the accompanying drawing, in which:—

Figure 1 is a perspective view of a part 50 of an edge setting machine embodying the invention. Fig. 2 is a detail elevation view of the burner attachment, *per se*. Fig. 3 is a cross section on the line 3—3 of Fig. 4. Fig. 4 is a detail top plan view of a portion of 55 the burner.

Referring now to the accompanying draw-

ing, in which like numerals of reference designate like parts in all of the figures, 1 represents the edge setting machine, which may be of any approved type or construction as, 60 for instance, the Rossmoyer edge setting machine, as it is known in the trade, and this machine includes the support 2 for the burnishing tool in which the shank 3 of the tool is reversibly mounted, the head 4 of the 65 tool having the diverging burnishing tools proper 5 and 6 attached thereto in the usual manner.

7 is the usual rest and 8 is the usual gas supply pipe that delivers into a T 9 from 70 which the lateral branches to each side of the machine (when the machine is a double one) are extended. Each lateral branch includes a cutoff valve 10, and a coupling 11 by means of which the burner proper is secured to the 75 lateral pipe.

The burner proper, which constitutes the essential part of present invention, consists of a pipe 12 that is coupled at 11 to the lateral pipe and delivers into a valve 13 to 80 register with the through port 14, the latter also registering with the outlet burner pipe 15 that is secured in the valve shell or casting 13 and extends to a position in proximity to the front burnishing tool so that its discharge end 16 will direct a flame against the rear of the front tool, be it 5 or 6, accordingly as to which of the tools 5 or 6 is in use.

The valve 13, it will be noticed, has a vertical duct 18-23 that merges with the cock bore 17 in which the valve cock 19 is located, the cock 19 having a port 22 to effect communication between the sections 18-23 of the vertical duct. The duct 23 discharges 95 into an auxiliary burner pipe 24 that is carried down and parallel to the pipe 15 to which it may be secured, if desired, by brazing, soldering or any other well known manner. The auxiliary pipe 24 extends forwardly and has its front end turned back, as at 25 to direct a flame on the back face of the rear or idle burnishing tool. The cock 19 has an elongated recess 20 to coöperate with the stop 21 whereby the turning movement of the cock 19 may be limited to "off" and "on" positions.

In the practical use of my invention, it will be observed, that flames may be kept directed on both the active and the inactive 110 tool, or cut off from the inactive tool, and the relative heating intensity of the two

flames can be adjusted by manipulating the cock 19 to cut off more or less of the gas supply to the auxiliary burner outlet end 25.

In practice, the fore-part iron has to do more work than the shank iron and therefore with my burner, the flames can be so adjusted as to keep both irons at the proper temperature to burnish the edge correctly. If the operator has a lot of shoes to do that have the same edge all the way around, he can turn off the auxiliary burner section and save that much gas.

In the art as heretofore practised with the single burner, the difficulty is that both irons could not be kept at the proper heat; one iron would get too cold, while the other would get too hot. This trouble is overcome by the use of my invention and the operator is therefore enabled to do more work and better work in less time, because he can adjust the burner to heat each iron correctly and keep the irons at the proper temperature while working with the machine. Again, with the old style single flame burner, the operator must handle his work twice in order to accomplish good results, whereas with the use of my invention he can burnish the fore-part of the edge and the shank while he has the shoe in his hands, thus handling his work but once and thereby saving time and labor.

From the foregoing taken in connection with the accompanying drawing, it is thought the complete construction, operation and advantages of my invention will be readily understood by those skilled in the art to which it relates.

What I claim is:

1. The combination with the rotatable tool head of an edge burnishing machine and the pair of burnishing tools divergently pro-

jecting from said head; of a double-flame burner having its discharge orifices located to direct separate flames one on each of the tools and means for adjusting the relative heating effect of the respective flames.

2. The combination with an edge setting machine having a reversible burnishing tool head provided with a pair of burner irons, of means for heating both of said irons, said means comprising a gas supply pipe, a shut-off valve in said supply pipe, and a burner attachment comprising a pipe connected with said gas supply pipe, a control cock and a main burner discharge pipe for directing a flame against the front or operative one of the tools, and an auxiliary burner pipe connected with said control cock and arranged with its discharge orifice to direct a flame against the other or inactive tool, said control cock having provisions for shutting off and regulating the flow of gas through said auxiliary burner pipe substantially as shown and for the purposes described.

3. As a new article of manufacture, a heating burner attachment for edge setting machines comprising a cock, a main burner pipe extending from said cock, an auxiliary burner pipe extending from said cock, and an inlet pipe extending from said cock and adapted to be attached to a source of gas supply, said cock having ducts for conveying the gas from said inlet pipe to said main and auxiliary burner pipes, said cock having provision for controlling the flow of gas to one of said burner pipes, all being arranged substantially as shown and for the purposes described.

ALVADER D. HORNE.
